OIL BURNER

Herman E. Josephson, Gloucester, Mass., assignor,
by mesne assignments, to Gloucester Products
Company, Gloucester, Mass., a corporation of
Massachusetts

Application November 10, 1932, Serial No. 642,017

3 Claims. (Cl. 158—86)

This invention relates to oil burners of the type used in cooking ranges, domestic heating apparatus, and the like.

Burners of this type must be installed in a great variety of makes, sizes and styles of ranges and other heating apparatus which naturally differ widely in dimensions and design. In addition, some ranges will be provided with water backs and others with water fronts, while still others have neither. In order to realize the maximum operating efficiency from the burner, the installation must be made both with reference to such features of design and also with regard to the requirements of the user. For example, in some installations a continuous supply of hot water from the range is an important requirement, whereas this may be a minor matter with other users. Some ranges, also, are so designed that a burner can easily be installed and adjusted to meet the requirements of that particular range, while in others, especially those of old styles, or which have seen hard usage, the matter of properly installing the burner may be much more difficult.

The present invention is especially concerned with these considerations. It aims to devise a burner which will be universal in a very substantial measure, and which can be used satisfactorily in an unusual variety of sizes, makes and styles of cooking and heating apparatus. In addition, it is an object of the invention to simplify the manufacturing and installing operations, and to provide a greater degree of flexibility in the operating conditions so as to satisfy a wider range of demands on the part of the user.

The nature of the invention will be readily understood from the following description when read in connection with the accompanying drawings, and the novel features will be particularly pointed out in the appended claims.

In the drawings,

Figure 1 is a plan view of an oil burner constructed in accordance with this invention but with the sleeves and covers removed;

Fig. 2 is a front elevation of the apparatus shown in Fig. 1 but illustrating also the lower ends of the sleeves;

Fig. 3 is a vertical sectional view approximately on the line 3—3, Fig. 1; and

Fig. 4 is a sectional view approximately on the line 4—4, Fig. 1.

The burner shown in the drawings is of the two unit type and comprises right and left burner bases, indicated in general at 2' and 2, respectively. Referring first to the right-hand unit it

will be seen that the base 2 is of a general form similar to those used heretofore in that it includes inner and outer concentric grooves 3 and 4, respectively, with perforated metal sleeves or cylinders 5, Fig. 3, resting on the walls of the grooves and providing annular concentric combustion chambers located immediately above the respective grooves. The central space within the inner sleeve and the annular space between combustion chambers are closed at their upper ends by a removable sheet metal cover 6', Fig. 3. Wicks (not shown) may be used in the grooves 3 and 4 to facilitate the starting operation in the manner common in this art. The other burner unit is substantially a duplicate of that just described, and the corresponding parts are indicated by the same, but primed, numerals.

In using such burners in a range it is important to the production of the best results that the two units be substantially centered under the two front covers of the range. Also, it is desirable that such burners be located at a certain definite distance from the water front or water back of the range if a relatively large supply of hot water is required, and that they be located differently if it is more important that a greater proportion of the heat be used for baking purposes. In addition, it is absolutely essential that each base be located in an exactly level position. In order to meet these requirements provision is made for an approximately universal adjustment of the burner units.

As shown in the drawings, both units are supported on a stand which comprises a foot 6, a bracket 7 mounted thereon, an upright rod 8 carried by the bracket, and a bar 9 supported on said rod. The two units are mounted on opposite ends of the bar. The foot comprises a plate-like member provided with an approximately central hole, and a bolt 10 extending through this hole and through the bottom of the stove cooperates with corner bolts or screws 12 and 13 to clamp the foot rigidly to the stove. At its rearward end the foot is provided with a raised boss having a flat top on which a slotted extension of the bracket 7 rests, and a bolt 14 projects through the slot in this extension and is threaded into the boss to secure the bracket firmly to the foot. This arrangement, however, permits the adjustment of both burners toward and from the back or front of the stove and a swinging adjustment of them on the foot to align them properly in the fire box in the event that difficulty is encountered in locating the foot in just the desired position. The rod 8 is secured rigidly in the bracket 7 while the bar 9 is adjust-

able vertically on said rod and is secured in its adjusted position by the set screw 15, Fig. 4. Consequently, the burners can be set at any desired elevation in the fire box.

5 The two burner units are supported on the opposite ends of the bar 9. Referring again to the right-hand unit, as shown more especially in Figs. 1 and 3, it will be seen that this unit is carried by a bar or fitting 16 which extends transversely across one end portion of the bar 9 immediately under the burner base 2. On its lower side the bar or fitting 16 is provided with a boss 17 having a rounded surface, preferably of substantially the shape of a section of a sphere or ball. 10 15 This boss rests in the concave surface of a washer or socket member 18 having a central hole therethrough, and a bolt 20 projects loosely through the bar 16, socket member 18, and through a slot 21 extending lengthwise of the supporting bar 9, so that by tightening up the nut on this bolt all 20 three of these parts can be secured together. The bar 16 is rigidly secured to the bottom of the burner base 2 by screws 22 and 23. Its ball and socket connection with the bar 9 therefore permits the adjustment of the burner base into various positions of inclination relatively to the stand, and it is a simple matter, therefore, to adjust the base into a level position and then to secure it in that position by tightening up the nut on the bolt 20. The other burner unit is similarly 25 supported and consequently, each unit can be leveled independently of the other. Frequently this is an important advantage due to unfavorable conditions under which a burner must be installed.

30 35 This mounting of the burner units also has the important advantage of permitting their adjustment toward and from each other to center them properly under the front covers of a range.

40 In this burner the two rings of the burner base preferably are made integral with each other, and they are connected rigidly together by web portions 24. No communication, however, is provided between the grooves 3 and 4 in the two 45 rings. On the contrary, independent oil feeds are provided to these grooves so that either the inner or outer combustion chamber may be operated without the other whenever desired. A unique arrangement also is provided for conducting the oil or fluid fuel to the grooves. Referring 50 again to the right-hand burner base 2, as shown in Figs. 1, 2 and 3, it will be seen that independent feed lines 25 and 26 lead, respectively, from the supply main 27 through regulating valves 28 and 29 to the inner and outer rings 3 and 4, respectively. The feed lines may consist of copper tubing equipped with compression fittings of a well known type. Instead of running them directly to the grooves 3 and 4, however, they are led into connectors 30 and 31, respectively, of a special form. As shown in Fig. 3 the connector 30 has a reduced neck fitting in a slot in one end of the bar 16; it has a substantially straight hole formed through it from top to bottom, the feed line leading into it at one side, and the lower end of the hole is closed by a removable plug 32. The other connector 31 is a duplicate of that shown at 30 and is supported in a slot formed in the opposite end of the bar 16. At their upper 60 65 70 ends the two connectors enter smooth walled sockets in the burner base 2 and their extreme end faces bear against the bottom of the burner base, gaskets preferably being interposed between the flat abutting surfaces of the connectors and the base. These parts are held securely in their op-

erative positions by the screws 22 and 23 acting through the bar or fitting 16. The other burner unit is similarly equipped.

5 This construction is of advantage in installing the burner since by loosening the screws 22 and 23 the pressure on the heads of the connectors may be relieved sufficiently to permit them to be turned into any angular relationship to the burner base, so that the feed lines can be run to the connectors through either end or the front of the stove, or 10 from any other direction. Much of the time spent in bending and fitting the feed lines thus is eliminated. In addition, the straight holes through the connectors facilitates the cleaning 15 of these parts since a cleaning tool can be run entirely through either connector after the plug 32 has been removed. If any individual combustion chamber fails to perform satisfactorily, it is a simple matter with this arrangement to find out where the difficulty lies and even to take down 20 the feed line running to that particular chamber without disturbing any of the other connections.

25 The invention thus provides a burner construction which can readily be installed in an unusual variety of sizes, makes and styles of cooking or heating apparatus. In addition certain of the manufacturing and installing operations are facilitated. This construction also makes it possible to operate any one of the four combustion 30 chambers, or any combination of them, whenever desired which is an important practical advantage under many conditions.

35 While I have herein shown and described a preferred embodiment of my invention, it will be understood that minor changes may be made within the spirit and scope of the invention.

Having thus described my invention, what I desire to claim as new is:

40 1. In an oil burner, the combination of a burner base having an oil holding groove on the upper face thereof, a stand on which said base is mounted, a bar interposed between said base and said stand, said bar having a rounded boss, a socket member for engaging said boss, said socket member and bar supporting said burner base for adjustment into various inclinations relatively to said stand, and an upright bolt extending through said bar, said socket member and a part of said stand for securing them rigidly in their 45 50 adjusted relationship.

45 2. In an oil burner, the combination of a burner base, a stand on which said base is mounted, a bar interposed between said base and said stand, said bar having a rounded boss, a socket member for engaging said boss, said socket member and bar supporting said burner base for adjustment into various inclinations, and said socket member and bar being slidable together on said stand, means for securing said base to said bar, and a bolt extending through said bar, socket member and a portion of said stand for securing the base in its adjusted position on said stand.

55 3. In an oil burner, the combination of an oil burner unit including a base having two oil grooves, perforated sleeves supported on the walls of said grooves and cooperating with them to provide two independent combustion chambers, a stand on which said base is mounted, a bar interposed between said base and said stand, said bar having a rounded boss, a socket member for engaging said boss and cooperating with said bar to support said burner base for adjustment into various angles of inclination relatively to said stand, said stand including a part on which said 60 65 70 75 80 85 90 95 100 socket member and bar are slidably adjustable together, means for securing said bar and said socket member rigidly to said stand, two upright connectors extending downwardly from the bottom of said base and having holes therethrough communicating with said respective grooves, oil

supply lines leading into the sides of said connectors, said bar having slotted ends embracing said connectors, and screw threaded means for acting through said bar to clamp both connectors removably to the bottom of said base.
